ELECTRICAL CONNECTOR

Kemper M. Hammell, Harrisburg, Pa., assignor to AMP Incorporated, a corporation of New Jersey

Application April 20, 1955, Serial No. 502,697

4 Claims. (Cl. 339—258)

This invention relates to electrical connectors and more particularly, in a connector assembly wherein the parts are designed for fast and permanent assemblage, to an improved sheet metal receptacle which grips under spring pressure a mating sheet metal tab.

In the art of coupling a pair of conductors with solderless connectors wherein the parts forming the assembly are secured together by the friction afforded through one part having spring means bearing against a surface on the other part, adequate spring pressure must be provided to satisfy mechanical requirements, e. g. stability against accidental disconnection, while a sufficient area of electrical contact must also be provided to attain the current-carrying capacity usually desired of such connectors.

The amount of metal in the receptacle available to obtain both the mechanical and electrical characteristics desired, however, is limited. It has been the practice, therefore, to concentrate all the available spring pressure at points or along lines of the tab to achieve a good mechanical connection, assuming that good electrical characteristics flow from the high contact pressure thereby obtained.

Reducing the places of contact to lines and points, albeit at high contact pressure, more or less reduces the current rating of the connection, but more disadvantageously such contact is highly subject to corrosion in use even under good conditions, primarily due to accelerated oxidation caused by the heat inherently generated in the assembly. Thus, although a connection in which reliance is placed on line and point contact under high pressure may initially perform satisfactorily even under fairly heavy current loads, such a connection tends to deteriorate at a fairly high rate and to fail from corrosion.

It is, therefore, an object of the present invention to provide an electrical connector assembly wherein the parts may be quickly assembled in permanent installation yielding a connection which retains high quality mechanical and electrical characteristics throughout the life expectancy of the equipment associated therewith. Another object is to provide in an electrical connector assembly an improved sheet metal receptacle for receiving under spring pressure a mating tab. To these purposes an optimum area of contact between the elements is provided without reducing the contact pressure below the minimum necessary to secure the assembly from disconnection in normal use whereby, while the perimeter of the contact area may be subject to corrosion, a central portion of such area will be insulated and protected from corrosive factors thus assuring an electrical connection of long life and high quality.

Other objects and attainments of the present invention will become apparent to those skilled in the art upon a reading of the following detailed description when taken in conjunction with the drawings in which there

2

is shown and described a preferred embodiment; it is to be understood, however, that this embodiment is not intended to be exhaustive or limiting of the invention but is given for purposes of illustration in order that others skilled in the art may fully understand the invention and the principles thereof and the manner of applying it in practical use so that they may modify it in various forms, each as may be best suited to the conditions of a particular use.

- 10 In the drawings:
Figure 1 is a perspective view of the two elements of a connector assembly illustrating the invention;
Figure 2 is a sectional view of the receptacle element taken at line 2—2 of Figure 1;
15 Figure 3 is a sectional view similar to that of Figure 2 but with the tab element in connective relationship with the receptacle element;
Figure 4 is a sectional view taken at line 4—4 of Figure 3;
20 Figure 5 is a sectional view taken at line 5—5 of Figure 2; and
Figures 6a to 6d are fragmentary cross-sectional views taken from Figure 3 for illustrating certain mechanical deficiencies encountered in the forming process of the
25 connector assembly.

A connector assembly illustrative of the invention includes a tab element and a receptacle element for receiving and frictionally gripping the tab, generally designated at 1 and 3 respectively in Figure 1, the elements being 30 provided with ferrule means by which each is attached in electrical connection with the ends respectively of a pair of leads 5 to be coupled. Typically such ferrule means include barrels 7, each having a pair of ears 9, curled about and compressed into tight mechanical and 35 electrical engagement with the bared ends of leads 5 and barrels 11, each having a pair of ears 13 wrapped around and supporting the insulation of the leads.

The connector elements 1 and 3 may conveniently be 40 fabricated according to conventional blanking and forming techniques from any suitable malleable sheet metal stock, such as half to three-quarters hard brass, bronze or the like, which will increase in resilience and hardness upon being subjected to a cold-forging or coining operation. As thus fabricated, in the illustrated embodiment of my invention element 1 takes the form of a substantially flat rectangular tab having stop shoulders 15 which engage the front sidewalls of receptacle element 3 thereby to define the limit of insertion of the tab within the receptacle. An indentation or dimple 17 is centrally 50 located on at least one, and preferably both active surfaces of tab 1 to form with boss 19 in receptacle 3 a detent means to be more particularly described.

To provide for receiving and retaining tab 1 in spring-locked electrical and mechanical engagement, receptacle 55 element 3 includes a base or floor portion 21 from opposed side edges of which extend a pair of flanges 23 having inturned ends 25 overlying and spatially disposed from base portion 21, as best shown in Figures 2 to 5. As thus arranged, base portion 21 and flanges 23 define 60 an open-ended channel of slightly greater width and height than tab 1 which may therein be inserted. Suitably anchored at longitudinally spaced points along base portion 21 is a spring 27 in the form of a flat strip which is bowed out of the plane of base portion 21 and into the channel of the receptacle thereby to bias under pressure tab 1 into engagement with ends 25 of flange 23. Spring 27 may conveniently be fashioned integrally with base portion 21 in the forming operations for the receptacle. To this end a pair of substantially parallel longi-

tudinal slots 29 cut in base portion 21 define the spring strip 27 which thus has its ends integral with base 21. Also in the forming operation strip 27 is reduced in thickness as compared to the original thickness of the sheet metal stock by a cold-forging or coining operation whereby to impart the desired spring characteristics thereto, such as hardness and resilience.

As thus constructed insertion of tab 1 in the receptacle depresses spring 27 which bears against the undersurface of the tab that is in turn supported by flange ends 25. A centrally located boss 19, preferably raised on the surface of spring 27 during the coining operation performed thereon, cooperates with either of indentations 17 of tab 1 to provide a detent which adds to the tensile or pull-off strength of the connection. It will be observed from Figures 3 and 4 that in order to be withdrawn from its connected relationship with the receptacle, tab 1 must depress spring 27 an amount equal to the height of the boss above the plane of the spring thereby adding to the spring pressure which has to be overcome. Boss 19 and indentation 17 may take any suitable complementary form which will result in the smooth camming of spring 27 downwardly upon either insertion or withdrawal of the tab. For example, the boss and indentation may present semi-spherical surfaces as shown, or alternatively, indentation 17 may simply be a hole extending through the tab.

To avoid the concentration of the spring pressure afforded by spring 27 solely at points or along lines of contact between tab 1 and receptacle 3, boss 19, while similar in configuration to indentation 17, is designed to have smaller relative dimensions. Shoulders 15 permit insertion of the tab within the receptacle at least to the extent that results in centering of indentation 17 over boss 19 which then is free from contact with the tab. As a result, area contact between the tab and spring surfaces may be achieved, as will be explained. In this connection in Figure 3 the undersides 31 of ends 25 are shown in flat abutment in area contact with the upper surface of tab 1. While this may be desirable from an electrical conductivity standpoint, such area contact is extremely difficult to achieve in practice; surfaces 31 must be precisely coplanar while tab 1 must be absolutely flat and free from the edge curvature due to blanking or burrs along the tab sides as a result of employing stamping operations in the forming process. Neither of these conditions can be satisfied practically where blanking and forming processes are employed, hence, in reality only a line contact on the tab is obtained with surface 31, various possible conditions being shown in Figures 6a to 6d, such contact being unreliable electrically due to its vulnerability to corrosion.

As shown in Figure 5, spring 27 is bowed inwardly of the receptacle channel about radii of curvature R₁ at the extremities that are substantially less than the radius of curvature R₂ of the central portion of the strip to define a central slightly-bowed plateau which is flattened, Figure 4, upon depression of the spring by tab 1. The central portion of the area of contact thus attained is sufficiently isolated from all points which may be attacked by corrosion that the connection may support high current loads over a prolonged period. To gain as much area of contact as possible without unduly decreasing contact pressure, slots 29 should be located as near as possible to the side edges of base portion 21, thus increasing the width of the contact area while adding to the volume of metal comprising the spring.

The primary conductive path between the tab and receptacle is seen to be the flattened upper surface of spring 27 and the contacted portion of the undersurface of the tab. Thus, spring 27 has the dual function of mechanically locking and electrically contacting the tab. Mechanically, the spring may vary in form and dimension so long as electrically a minimum area of contact is as-

sured. In this connection the length dimension of the contact area is not critical since the minimum requirements in this respect are usually greatly exceeded. For example, the edge contact illustrated in Figure 6 extends substantially the length of the tab, but the contact width along the surfaces shown has been found in practice not to exceed 0.015 inch, and usually less, which is inadequate. Oxide penetrations from both sides of such line contact results in complete failure of the connection within 500 hours in life tests simulating actual service by temperature cycling. A contact width of 0.030 inch, however, has been found to be satisfactory in that the connection will not fail in temperature cycling until after at least 1500 hours time which is the lowest commercially acceptable limit. Preferably the contact width is 0.060-0.080 inch which provides an adequate safety factor and operable time of at least 3500 hours for exceeding in all probability the life of any device utilizing the connection.

To achieve a contact width of 0.060-0.080 inch, in view of the small size for the receptacle portion of receptacle element 3, typically in the order of 0.400 inch which may accommodate a spring 0.300 inch in length, the plateau of spring 27 must be nearly flat with only a slight bow or crown at radius R₂. In a receptacle of this size a maximum spring deflection of 0.008 inch will typically accommodate the thickness of the tab and the height of boss 19, but in 0.300 inch this amount of spring deflection cannot be absorbed by a spring bowed in accordance with radius R₂ without being forced overcenter. The radius of curvature R₁ at the spring extremities must be sufficiently smaller than radius R₂ to raise the nearly flat spring plateau above the plane of floor 21 far enough to avoid depression of the spring below the plane of the floor, thus effectively increasing the spring length.

I claim:

1. An electrical connector for receiving a substantially flat rectangular tab having an indentation in at least one face comprising a base portion, oppositely disposed side flanges overhanging and forming with said base portion a receptacle for receiving the tab, a boss on said base portion adapted to fit within the indentation to provide a detent for resisting withdrawal of the tab from the receptacle, said boss having dimensions smaller than the indentation, relative to the general plane of the contact surfaces of said base portion and the tab respectively, so as to be free from forceful engagement with the tab upon centering the indentation over said boss.

2. An electrical connector for receiving a substantially flat rectangular tab having an indentation in at least one face comprising a base portion, oppositely disposed side flanges overhanging and forming with said base portion a receptacle for receiving the tab, said base portion including a resilient strip convexly bowed lengthwise of said receptacle and adapted to spring-bias the tab against said flanges and to be at least partially flattened to provide an area of electrical contact with the tab, a boss on said member adapted to fit within the indentation to provide a detent obstructing removal of the tab from the receptacle, the corresponding dimensions of said boss being smaller than the indentation so as to be free from forceful engagement with the tab upon centering the indentation thereover.

3. An electrical connector substantially as set forth in claim 2 wherein said strip is defined by two parallel slots in said base portion and is bowed out of the plane of said base portion with radii of curvature at the end portions substantially smaller than the radius of curvature of the central portion thereof.

4. An electrical connection comprising a receptacle having a base portion and opposed side flanges overhanging said base portion, said base portion including a resilient strip convexly bowed lengthwise of said receptacle, and a

substantially flat tab received within said receptacle and spring-biased by said strip against said flanges causing said strip to become flattened over a central portion of its length, detent means for resisting removal of said tab including a boss and dimple respectively on said strip and tab within the flattened part of said strip, the corresponding dimensions of said boss being smaller than said dimple so as to be free from forceful engagement with the tab.
